UNITED STATES PATENT OFFICE.

CASPER E. BLANCHARD, OF CHICAGO, ILLINOIS.

BOTTLE-CLOSURE.

1,361,789.

Specification of Letters Patent.

Patented Dec. 7, 1920.

Application filed June 10, 1920. Serial No. 387,925.

To all whom it may concern:

Be it known that I, CASPER E. BLANCHARD, a citizen of the United States, and a resident of Chicago, in the county of Cook and State of Illinois, have invented a new and useful Improvement in Bottle-Closures, of which the following is a full, clear, and exact description.

My invention relates to improvements in bottle closures, and it consists in the combinations, constructions, and arrangements herein described and claimed.

The present invention is designed to be an improvement over that disclosed in my prior application, Serial No. 343,779, filed Dec. 10, 1919. In said prior application a bottle closure was disclosed which was submitted in the neck of a bottle and which was designed to be torn when an attempt to remove the closure was made, in order to prevent the refilling of the bottle or the replacement of the closure without detection.

An object of my invention is to provide a bottle closure which does not require to be cemented in the neck of a bottle, but which when inserted in the neck will, owing to its peculiar structure cling to the neck so that when an attempt is made to remove the closure, it will tear.

Another object of my invention is to provide a device in which the closure has a body portion and a cap with a metal cover plate, which not only protects the cap but also secures it to the body portion of the closure.

Other objects and advantages will appear in the following specification, and the novel features of the invention will be particularly pointed out in the appended claims.

My invention is illustrated in the accompanying drawings, forming part of this application, in which—

Figure 1 is a section through the neck of a bottle showing the closure in its normal position before being cut.

Fig. 2 is a section through the closure with the cover and ball valve removed.

Fig. 3 is a section through the cap.

Fig. 4 is a plan view of the cover.

Fig. 5 is a section through the cover in perspective.

Fig. 6 is a section through the neck of the bottle, showing portions of the closure removed, and the liquid flowing out of the bottle.

In carrying out my invention, I provide a

body portion 1 (see Fig. 2), having its outer wall substantially cylindrical in shape. The closure is preferably made of rubber. The lower interior walls 2 taper inwardly, forming the passage ways 4 and 5, on which rests the ball valve 7, when the bottle 24, is in its normal upright position. Between the curved surface 3 and the top 8 of the body portion 1, I provide inwardly tapered interior walls 9, so that at the point 10, where the body portion 1 meets an outwardly extending flange 11, the rubber is the thinnest. At the end 21 of the passage way 5 of the body portion 1, the walls 22 are slightly flared out and are also substantially thinner.

A cap 12 with upstanding lugs 13 has recessed portions 14, extending from the under side of the cap 12 to above the upper surface of said cap. I also provide in the cap 12 a lug 19 extending downwardly into passage way 4 of the body portion 1, said lug 19 having a recess 20 extending up into it from the underside.

A metal cover plate 15 has perforations 16 adapted to come in alignment with lugs 13, as shown in Figs. 1 and 3. The inwardly bent portion 17 of the cover plate 15 is substantially one-half the width of the flange 11. The diameter of the cover plate 15 is 85 slightly greater than the outside diameter of the flange 11.

When it is desired to pour out some of the liquid contents, the lugs 13 are cut off, so that the recesses 14 now become openings 90 into the interior of the bottle. When the bottle is tipped, the ball valve 7 will roll down the curved walls 3, thus permitting the liquid 23 to flow past the valve seat 6 and out of the openings 14. When the bottle is placed in an upright position, the ball valve 7 returns to its seat 6, thus effectually closing the bottle, and preventing evaporation. I have found that by making the walls 22 of the body portion 1 thin and flared out, a 100 much better grip is obtained by the closure on the neck of the bottle. If any attempt is made to remove the closure, as for instance, where one inserts a knife underneath the edge of the metal cover plate 15 and pries 105 upwardly, the closure will be torn at the point 10 so that the attempt to remove the closure will be easily detected.

I claim:

1. The combination with a cylindrical 110 bottle neck of a substantially cylindrical resilient closure comprising a body portion

having outwardly flaring relatively thin walls at one end thereof and being provided with a laterally extending flange at the other end thereof, the junction between the flange 5 and the body portion being relatively thin, a cap arranged to abut the flange on said body portion, and means for securing the cap to the flange.

2. The combination with a cylindrical 10 bottle neck of a substantially cylindrical resilient closure comprising a body portion having outwardly flaring relatively thin walls at one end thereof and being provided with a laterally extending flange at the other 15 end thereof, the junction between the flange and the body portion being relatively thin, a cap arranged to abut the flange on said body portion, means for securing the cap to the flange, and a ball valve carried by the 20 body portion on the interior thereof and adapted to be unseated when the bottle is tilted.

3. The combination with a cylindrical bottle neck of a closure comprising a substantially cylindrical body portion having flaring and relatively thin walls at one end of the body portion arranged to engage the interior wall of the bottle, a laterally extending integral flange at the other end of 30 the body portion, the junction between the flange and the body portion being relatively thin, the interior walls of the body portion

tapering inwardly from each end of the body portion, a valve seat formed by the converging walls, a ball valve normally 35 carried on said valve seat, and a cap arranged to rest on said flange, said cap having outwardly extending hollow lugs adapted to be cut off to permit the outflow of the contents of the bottle and the entrance of air. 40

4. The combination with a cylindrical bottle neck of a closure comprising a substantially cylindrical body portion having flaring and relatively thin walls at one end of the body portion arranged to engage the 45 interior wall of the bottle, a laterally extending integral flange at the other end of the body portion, the junction between the flange and the body portion being relatively thin, the interior walls of the body portion 50 tapering inwardly from each end of the body portion, a valve seat formed by the converging walls, a ball valve normally carried on said valve seat, a cap arranged to rest on said flange, said cap having outwardly extending hollow lugs adapted to be 55 cut off to permit the outflow of the contents of the bottle and the entrance of air, and a cover plate having openings arranged to receive the upstanding lugs of the cap, the 60 edges of the metal cover plate being bent around the flange for holding the cap to the flange.

CASPER E. BLANCHARD.
